UNITED STATES PATENT OFFICE.

EARLE M. JONES, OF MINNEAPOLIS, MINNESOTA, ASSIGNOR TO O. B. McCLINTOCK COMPANY, OF MINNEAPOLIS, MINNESOTA, A CORPORATION OF MINNESOTA.

DESIGN FOR A CLOCK.

Application filed June 5, 1922. Serial No. 2,536. Term of patent 14 years.

To all whom it may concern:

Be it known that I, EARLE M. JONES, a citizen of the United States, residing at Minneapolis, in the county of Hennepin and State of Minnesota, have invented a new, original, and ornamental Design for Clocks, of which the following is a specification, reference being had to the accompanying drawing, forming part thereof.

Fig. 1 is a front elevation of a clock, showing my new design.

Fig. 2 is an edge view of the clock.

I claim:

The ornamental design for a clock, as shown.

EARLE M. JONES.
